(57) CLAIM

The ornamental design for a front vehicle grille, as shown and described.

DESCRIPTION

FIG. 1 is a front perspective view of the grille;
FIG. 2 is a left elevational view of the grille;
FIG. 3 is a front elevational view of the grille;
FIG. 4 is a top plan view of the grille;
FIG. 5 is a rear elevational view of the grille;
FIG. 6 is a bottom plan view of the grille; and,
FIG. 7 is a right elevational view of the grille.
The broken lines shown in FIG. 1 of the drawing are for illustrative purposes and form no part of the claimed design.
